UNITED STATES PATENT OFFICE.

WILLIAM J. CUNNINGHAM, OF CHICAGO, ILLINOIS, ASSIGNOR OF ONE-HALF TO
GRIFFEN H. DEEVES, OF CHICAGO, ILLINOIS.

CARBURETER.

1,162,041.

Specification of Letters Patent. Patented Nov. 30, 1915.

Application filed December 23, 1914. Serial No. 878,705.

To all whom it may concern:

Be it known that I, WILLIAM J. CUNNINGHAM, a citizen of the United States, residing at Chicago, in the county of Cook and State of Illinois, have invented certain new and useful Improvements in Carbureters, of which the following is a specification, reference being had therein to the accompanying drawing.

10 My invention relates to carbureters for internal combustion engines, and consists of the matters hereinafter described and then pointed out in the appended claims.

In the accompanying drawings which 15 illustrate the preferred embodiment of my invention Figure 1 is a view partly in side elevation and partly in cross sectional elevation of a carbureter constructed in accordance with my invention; Fig. 2 is a top 20 plan view of the parts of Fig. 1; Fig. 3 is a longitudinal vertical sectional view; Fig. 4 is a sectional view on the line 4—4 of Fig. 3; Fig. 5 is a sectional view on the line 5—5 of Fig. 1; Fig. 6 is a sectional view of one of the 25 mixing chambers or tubes and certain of its associated parts; and Fig. 7 is a view in rear elevation.

In the drawings the reference numeral 10 indicates a supply tank or chamber for the 30 gasoline or other liquid employed and preferably adapted to maintain a constant level of the liquid by any suitable means as now well understood in the art, and 11 is a supply pipe preferably rectangular in cross section and connected at one end to the supply and at its other end to the carbureting chambers in the carbureter casing, preferably by means of a series of spraying nozzles 12 of suitable capacity and arranged in a bank 40 along the bottom of the casing with their outlets at approximately the level of the gasoline level in the tank, so that the liquid may be drawn or sucked out of the nozzles in sprayed or atomized condition by the 45 passage of the air across or over their exposed ends as the engine draws the air through the associated carbureting chambers hereafter described. The fuel pipe is provided with a removable plug 13 to allow

access to the nozzles which are removably 50 connected to the bottom of the carbureter casing by any suitable means, such as by the screw connection shown. The casing of the carbureter is somewhat irregular in contour, and in the present embodiment of my 55 invention comprises a curved body 14, a straight rear wall 15 having an air port 16, a rearwardly inclined front wall 17, suitable side or end walls 18, and a top plate 19 provided with an outlet or discharge port 20 60 by which the explosion mixture passes into the inlet manifold or cylinders of the engine. The casing forms the air-intake chamber of the carbureter and the air supplied to it is preferably heated by the exhaust gases of the engine as by connecting the port 16 to a jacket surrounding the exhaust manifold in a manner now well understood in the art.

A series of carbureting chambers are 70 arranged in the casing, each chamber having communication at one end with the air supply and at its other end with the outlet or discharge port, and also receiving the discharge end of one of the spray nozzles. 75 These chambers are preferably provided by suitable tubes or pipes 21 which may be of any suitable size and shape and are supported in spaced relation across the interior of the casing by any suitable means such as 80 the transverse shelf 22 extending across the lower portion of the interior of the casing and provided with spacing partitions 23 extending to the rear wall 15 at approximately the lower line of the air port as 85 shown in Fig. 5. In the preferred form of construction each tube is bent to the form shown in elevation in Fig. 6 with its bend lying in the correspondingly curved bottom 14 of the casing where one of the spraying 90 nozzles 12 enters its bend to communicate with its interior; the long or substantially straight leg 24 of each tube extends upwardly in the chamber of the casing from its bent portion to the discharge port 20, 95 and the short or curved leg 25 terminates in a plane substantially level with the top of the shelf 22. The legs 24 pass between

the spacing partitions 23 so that they are spaced apart to allow the air from port 16 to pass or circulate between them for the purpose of heating them. The space above 5 the partitions and shelf 22 inclosed by the walls of the casing forms a hot air chamber with which the open ends of the legs 25 communicate. The entrance of the air to the legs 25 forming the air inlets of the carbureting chambers or tubes is controlled by a valve 26 arranged to allow a uniform volume of air to enter the tubes, though of course this volume may be varied to each tube by more or less opening the valve, which in the 10 present form consists of a plate slidably mounted in a bearing 27 on the casing and having an operating stem 28, the valve being movable transversely across the inlets or mouths of the tubes to regulate the draft of air passing thereto by the suction or low pressure produced in the engine cylinders by the induction strokes of their pistons, and arranged to afford an equal volume 15 of air to each tube in any position of the valve. The supply or draft of air when changed in one tube will be the same in all of them.

The outlets of the tubes at the discharge 20 are controlled by a throttle valve which 30 in the present form consists of a plate 29 slidably mounted in ways in the elongated top plate 19 of the casing to move laterally across the outlets of the tubes, and having an operating stem 30, it being understood 35 that both valves 26 and 29 are operated by the operator or chauffeur from his seat by any suitable connections not shown. The throttle valve 29 moves laterally across the outlets so that it may more or less open the 40 remote or farther tube 24 (as at the left hand of Fig. 3) and also successively cut in or cut out the other tubes so that one or any number of the tubes may be utilized to supply the explosive fuel to the engine. It is 45 therefore possible to partly or wholly open one of the tubes, or to open all of them. In order to enable the throttle valve to act quickly upon the carbureting tubes or chambers, the upper ends of the legs 24 are preferably brought into juxtaposition by suitably deflecting them all toward a common central point as clearly shown in Fig. 3, whereby the throttle valve may control all of them while passing through the minimum 55 stroke or travel.

The air, preferably heated by the engine exhaust, contacts with and so heats the upper legs of the carbureting tubes or chambers as it is drawn in by the suction of the 60 intake strokes of the engine pistons, and then enters in equal volumes into the lower legs of the carbureting chambers, and as it passes over the open ends of the nozzles draws the gasoline into it in sprayed or

atomized form to mix with it to form the explosive fuel which then is drawn through the discharge outlet to the engine. The nozzles being preferably of uniform capacity and all carbureting chambers having the same air supply in any position of the air 70 valve 26, the quality or richness of the mixture will be uniform in each chamber in operation, and by adjusting the throttle valve 29 to open the outlet of one chamber more or less, or to open any desired number 75 of chambers, the quantity or supply of explosive mixture of uniform quality or richness may be regulated or varied according to the requirements of speed or load of the engine. By my invention the air supply to 80 the several chambers is controlled by a single valve so that when the volume of air is changed in one it is uniform in all, and the fuel supply is controlled by a single throttle valve so that a variable supply of uniform mixture is available for different speeds and loads. Economy of fuel is assured as only the required amount of gasoline to make a perfect mixture is absorbed under various speeds and loads, it of course 85 being obvious that when the throttle valve closes any chamber the latter ceases to function as the air is not then drawn through it to displace the gasoline from the bore of its spraying nozzle. Greater flexibility of 90 the motor is provided as at any volume of fuel required, as by opening one or more of the legs 24, the proportions of air and gasoline are uniform in all the operating chambers and the fuel is thoroughly vaporized by 95 the heat of the legs 24; while I prefer to space the chambers apart and pass the air between their legs 24 in order to heat them, they may be otherwise disposed and the air (either heated or not) passed directly to 100 them.

In practice I prefer to restrict the cross-sectional area of each tube at or near the point where its spray nozzle feeds the gasoline, as shown for example in Figs. 1 and 6, 110 as this formation produces a more complete atomization or vaporization of the gasoline by the increased velocity of air drawn through the restricted passage at the nozzle by the engine suction, so that if the throttle 115 valve is set even for only a fraction or part of one of the legs 24 the gasoline is thoroughly atomized or vaporized. Also, my invention obviates all back pressure by eliminating the springs or weights usually employed to control the air intakes, and which create the back pressure that causes a slight hesitancy of the motor and impairs its flexibility and power. Furthermore, my invention obviates the defects arising in other 125 carbureters which draw in a certain amount of fuel after closing the throttle so that a quantity of liquid remains suspended in the

air and drops back into the air chamber, with the result that when the throttle is again opened the mixture is too rich in liquid and causes the motor to fluctuate until the quality is restored to a normal mixture; by my invention the closing of the throttle decreases the quantity of fuel without affecting its quality so that it is not enriched beyond the normal mixture.

10 While I prefer to make the chambers of uniform capacity and the nozzles of uniform supply, I may vary these features, as for example by increasing or varying the capacity of one or more of the chambers and associated nozzles so that an increased quantity of fuel would be furnished to the engine by such larger chamber; this would preferably be done by arranging the parts so that the larger chambers would be opened by the 15 throttle after one or more of the others.

The number of carbureting chambers or tubes may be varied depending on the desired size of the throttle area, as also may their form and shape, and the form and arrangement of the valves may also be varied. The supply of gasoline or other liquid to the spraying nozzle may be by any suitable means adapted to maintain the liquid therein at any point where it may be drawn into 20 the mixing tubes by the suction of the air, and the details of other parts may be changed.

I claim:

1. In a carbureter for internal combustion engines, a casing forming an air-intake chamber having an air supply, a series of independent carbureting tubes in the casing, each tube being reversely bent and having an inlet leg communicating with the air chamber and a discharge leg opening toward the engine, a liquid supplying nozzle in each tube intermediate its ends, a valve to uniformly vary the supply of air to the inlet legs, and a throttle valve to successively 45 open the discharge legs.

2. In a carbureter for internal combustion engines, a casing forming an air-intake chamber having an air supply, a series of independent carbureting tubes in the casing, each tube being reversely bent and having an inlet leg communicating with the air chamber and an outlet leg opening toward the engine, a liquid supplying nozzle in each tube intermediate its ends, the inlet legs of 50 the tubes being arranged side by side, a transversely movable valve to establish a uniform supply of air in the tubes, the outlets of the tubes being arranged side by side, and a throttle valve movable laterally along 55 the outlets to successively open them.

3. In a carbureter for internal combustion engines, a casing forming an air-intake chamber having an air supply, a series of independent U-shaped carbureting tubes in the

casing each communicating at one end with 65 the air chamber and discharging at its other end toward the engines, a liquid supplying nozzle in each tube intermediate its ends, the respective ends of the tubes being arranged in banks, a valve to uniformly control the 70 inlets of the tubes, and a throttle valve to successively open their chamber outlets.

4. In a carbureter for internal combustion engines, a casing having an air supply chamber, a series of independent carbureting 75 tubes spaced apart in the chamber and having legs of unequal lengths, the short leg of each communicating with the air chamber and the long leg passing through the air chamber and discharging toward the engine, 80 a liquid supplying nozzle in each tube intermediate its ends, the tubes being disposed side by side with their ends in banks, a valve to uniformly open the inlets in the short legs, and a throttle valve to successively 85 open the outlets of the long legs.

5. In a carbureter for internal combustion engines, a casing forming an air-intake chamber having an air supply port, a series of independent carbureting tubes in the 90 chamber having inlet and outlet legs, the inlet legs communicating with the air chamber and the outlet legs spaced apart and extending past the air port, a liquid supplying nozzle in each tube intermediate its ends, a 95 valve to uniformly vary the supply of air to the inlet legs, and a throttle valve to successively open the outlet legs.

6. In a carbureter for internal combustion engines, a casing forming an air chamber 100 having a supply port, a shelf in the casing, a series of independent carbureting tubes spaced along the shelf and each communicating at one end with the air chamber and extending past the air port to allow the air 105 to contact therewith and discharging at its other end toward the engine, a liquid supplying nozzle in each tube intermediate its ends, a valve in the air chamber to vary the supply of air to the tubes, and a throttle 110 valve to successively open the outlets of the tubes.

7. In a carbureter for internal combustion engines, a casing forming an air chamber having a supply port, a shelf in the chamber, 115 a series of independent carbureting tubes arranged in spaced relation along the shelf, each tube having a bent portion below the shelf and a long and short leg, the short leg of each tube communicating with the air 120 chamber and its long leg extending past the air port and discharging toward the engine, a liquid supplying nozzle in the bent portion of each tube, a valve in the chamber to vary the supply of air to the tubes, 125 and a throttle valve to successively open the outlets of the tubes.

8. In a carbureter for internal combusti-

tion engines, an air supply, a series of independent carbureting chambers each consisting of a U-shaped tube communicating at one end with the air supply and discharging at its other end toward the engine, the area of each chamber being restricted at the bend intermediate its ends, a liquid supplying nozzle in the restricted area of each chamber, means to control the supply of air to the

chambers, and means to successively open 10 the chamber outlets.

In testimony whereof I affix my signature in presence of two witnesses.

WILLIAM J. CUNNINGHAM.
